UNITED STATES PATENT OFFICE.

JOHN A. ALBERTONI, OF AKRON, OHIO.

MAILING TUBE.

Application filed August 6, 1920. Serial No. 401,794.

To all whom it may concern:

Be it known that I, JOHN A. ALBERTONI, a citizen of the United States, residing at Akron, in the county of Summit and State 5 of Ohio, have invented new and useful Improvements in Mailing Tubes, of which the following is a specification.

This invention relates to mailing tubes and similar containers, the invention residing 10 particularly in a new and novel means for closing the ends of such tubes.

Objects of the invention are to provide a strong, serviceable tube, the ends of which may be quickly, easily and securely closed 15 and which will be easily and quickly opened and consequently more convenient than tubes now in use.

Another object is to provide a closure means for the tube which may be securely 20 sealed and which may be opened without damage to the closure means, tube or the article contained therein so that the tube may be used indefinitely.

The above and other objects are accomplished by the novel construction, combination and arrangement of parts herein described and shown in the accompanying drawings in which I have illustrated a preferred embodiment of the invention, it being understood that changes may be made 25 and modifications resorted to which come within the scope of the claim hereunto appended.

In the drawings similar numerals of reference are employed to indicate corresponding parts throughout the several views, and in which—

Figure 1 is a perspective view of a mailing tube showing the closure means therefor in an open position.

Figure 2 is a perspective view of same showing the closure means in a closed position.

Figure 3 is a perspective view of a slip 45 clasp employed in carrying out the invention.

Figure 4 is a longitudinal sectional view of a tube constructed in accordance with this invention, showing one end of the tube open 50 and the other end closed.

Proceeding now to a detailed description

of the invention as illustrated in the accompanying drawings, the numeral 5 denotes the main body of the tube, the numeral 6 denotes a flexible tube which is pasted or otherwise secured over each end of the tube 5 so as to project beyond the end thereof. The outwardly projecting end of the flexible tube 6 is turned back inside itself and securely held in this position by the stitching 60 7, thus providing a hem 8. The said hem 8 is provided with an opening 9 into which a draw string 10 is passed so as to extend longitudinally through the hem 8, the same being brought outwardly through 65 the opening 9. One end of the draw string is passed through the loop 13 in the slip clasp 11 and the other end of the string 10 is passed through the loop 12 in said clasp. Both ends of said string 10 are brought together and passed through an eyelet 14 in the shipping tag 15 and are secured therein by the knot 16 which secures the free ends 70 of the string 10 together. The said slip clasp comprises a strip of metal or other 75 suitable material having its ends rolled back upon itself to form two parallel tubes or loops 12 and 13.

In use, one end of the tube is opened as shown in Figure 1, the desired article is 80 placed therein and the string 10 is drawn through the clasp 11, thus closing the end of the tube as shown in Figure 2. A knot 17 is then tied in the string 10 so as to hold the clasp 11 against the hem 8 and thus 85 secure the flexible portion 6 in a closed position.

If desired, the clasp 11 may be made of relatively soft material, such as lead, in which case it can be secured against sliding 90 movement by compression, thus forming a seal.

While I have shown and described a tube having a flexible projecting end 6, it is to be understood that one end of the tube may 95 be closed in any suitable manner and the flexible portion 6 applied to the other end thereof.

Having thus described my invention what I claim as new and desire to secure by Letters Patent is:—

In a device of the class described in com-

bination, a tube, a flexible extension secured to the end thereof, a string slidingly fixed around the free end of said extension so that the end of the tube may be closed by drawing the said extension together, a shipping tag secured to the free end of said string and a clasp slidably mounted on said

string, said clasp adapted to hold said extension in a closed position, substantially as herein set forth.

10

In testimony whereof I have hereunto set my hand.

JOHN A. ALBERTONI.
